PIPE WRENCH

Walter Roy Moore, East Orange, N. J., assignor
to The Billings & Spencer Company, a cor-
poration of Connecticut

Application October 1, 1930. Serial No. 485,753

11 Claims. (Cl. 81—70)

My invention relates to pipe wrenches.

It has among its objects to provide an improved pipe wrench, and, more particularly, an improved, simplified and strengthened wrench 5 of the chain type which has, in addition to the usual front and rear jaws on the side jaw plates, an improved and more conveniently usable front fittings jaw so disposed as to permit use of either the usual jaws or the fittings jaw at will, while 10 permitting a symmetrical disposition of the chain when co-operating with said front or rear jaws on the side jaw plates and avoiding cutting of the chain by the teeth of the front fittings jaw when the rear side jaws are in use. Still further 15 objects are to provide a new and improved construction of the fittings jaw and new and improved mounting and connecting means therefor, together with a new association and arrangement of that jaw with the wrench handle, 20 chain and other jaws, and a new pivot connection for the chain, all whereby new and improved results are obtained, and the wrench structure and its manufacture are improved and simplified. These and other objects and advantages 25 of my improved construction will, however, hereinafter more fully appear.

In the accompanying drawings I have shown for purposes of illustration, two embodiments which my invention may assume in practice.

30 In these drawings,—

Figure 1 is a side elevation of my improved wrench, certain of the parts being indicated in dotted lines and the chain being broken off to facilitate illustration;

35 Figure 2 is a vertical longitudinal section through the wrench between the jaw plates;

Figure 3 is a plan view of the construction shown in Figure 2;

Figure 4 is a front end view of the construction 40 shown in Figure 3;

Figure 5 is a section on line 5—5 of Figure 2;

Figure 6 is a section on line 6—6 of Figure 2;

45 Figure 7 is a detail perspective view of the fittings jaw;

Figure 8 is a detail perspective view of the chain connection screw, and

Figure 9 is a detail perspective view of a modified form of fittings jaw.

50 In this illustrative construction I have shown a handle 1 having usual hooks 2 and angular jaw plates 3 disposed on opposite sides of the latter, as well as a usual chain 4 adapted to co-operate in a usual way with the hooks 2; this construction including an improved construction

and arrangement of the fittings jaw and being otherwise improved as hereinafter described.

Considering the improved construction more particularly, it will be noted that the jaw plates 3 are connected to the opposite sides of the 60 body 5 by means of a bolt 6 (see Fig. 5). As shown, this extends through apertures 7, midway between the ends of the plates, and through a corresponding aperture 8 in the body 5, herein terminating in substantially triangular countersinks 9 which in turn are formed in opposite faces of the body 5 and extend toward the front end of the body. Herein, the parts are held in clamping relation by the bolt head and a nut 65 10, both engaging the outer faces of the plates 3. 70 Here it will also be noted that the usual offset front portion 11 of the body 5 which carries the projections 2, is not only provided with a usual chain slot 12 in its upper surface, but also provided in its lower surface with an elongated flat 75 seat 13 for the fittings jaw. Herein, this seat extends from the usual straight front face 14 of the portion 11, angularly downward to a point substantially under the axis of the bolt 6. There, it will also be noted that it terminates in a right 80 angle shoulder 15 providing a substantial abutment. Upon this seat 13 the fittings jaw 16 is disposed, with its rear end seated against the shoulder 15 and the jaw clamped in position 85 against the seat 13 by a suitable clamping member, herein a screw 17, disposed substantially midway between the aperture 8 and hooks 2 and having its head disposed in a suitable countersink 18 in the slotted upper surface of the portion 11 and its shank extending through that portion at 90 right angles to the seat 13 and received and connected in the fittings jaw 16 midway between its ends, herein by threading.

More particularly considering the fittings jaw, 95 it will be noted that the same is provided with a longitudinal chain groove 19, and with a pair of toothed portions 20 of substantial length on opposite sides of this groove, while a threaded aperture 21 is provided midway between the ends of the groove 19 and also spaced from the sides of 100 the latter to receive the threaded end of the screw 17. Herein, it will also be noted that the teeth 20 on the fittings jaw are disposed in the same direction as and at a slight angle to the adjacent teeth 22 on the under side of the front end of 105 the jaw plates 3. It will also be observed that herein the groove 19 is provided with a rounded bottom sloping more abruptly upward near its front end to permit ready passage of the chain and minimize cutting thereof, while the re- 110

mainder of this bottom is herein also in the form of transverse serrations corresponding to the teeth 20 and formed by having the points of the latter teeth removed to minimize wear on the 5 chain. It will also be noted that the teeth 20 of this fittings jaw are spaced substantially inward from the adjacent teeth 22 on the jaw plates 3 and extend substantially in front and in rear of the rear end thereof. Also, herein, one 10 set of these teeth 20 is disposed adjacent one plate 3, while the other set on the opposite side of the groove 19 is disposed adjacent the other plate 3. It will here be observed that, by reason of this construction, it is thus made possible to 15 provide two toothed surfaces 20 constituting in effect a plurality of laterally spaced fittings jaws, though formed herein on a single member, and located on opposite sides of the chain groove and adapted to grip a fitting very effectively with 20 a large total tooth length in engagement with the fitting when both of these teeth portions, or jaws 20, engage the same.

Next particularly considering the connections of the chain 4 which, when certain of the jaw 25 plates 3 are used, passes through the groove 19 in the new fittings jaw, it will be noted that this chain instead of being connected at a point adjacent the fittings jaw, is connected to the body 5 on the opposite end of the latter from the fittings jaw. In the structure shown, it will be 30 noted that the body 5 is herein provided with a shallow arcuate chain slot 25 in its rear end beneath a body portion of substantial section, while short lugs 26 are provided on opposite sides of the 35 same projecting below the body, and the slot terminates well in the rear of the bolt 6. These lugs 26 herein are in turn provided with registering apertures 27 adapted to receive a chain connection screw 28 on which a single elongated, normally depending, chain connecting link 29 for 40 the chain 4 is pivotally mounted for free movement between the lugs 26. Here it will also be noted that the screw 28 is provided with an annular shoulder 30 received in a corresponding and slightly larger recess 31 in one of the portions 45 26, while its threaded portion 32 is threaded into the bore of the other portion 26. It will also be observed that outside the shoulder 30 is an oppositely flattened head 33 adapted to be readily grasped by a wrench. When the jaw plates are 50 in position, this head 33 is disposed in a round aperture 34 in the inner face of one of the jaw plates 3, while the opposite end of the screw 28 is provided with a round extremity 35 disposed outside its threaded portion 32 and extending into an aperture 34 in the other jaw plate 3 corresponding to the aperture 34 previously described. Here it will also be noted that the jaw plates 3 which have these apertures 34 in one end thereof, are 55 also provided with corresponding apertures in their opposite ends adapted to receive the protruding ends of the member 28 and accordingly permit reversal of the jaw plates 3 when one set of teeth on the same is worn. Thus, it will be evident that a readily releasable connection is 60 provided for the chain connection 29 and one which will remain connected when the side jaw plates 3 are removed, as during use of the wrench on certain fittings.

65 In the use of my improved construction, it will be evident that when one set of the teeth 22 is to be used, the chain 4 will be extended around the pipe and caught over the hooks 2 in a usual manner, while when the other set of teeth 22 is in use, the chain will be similarly connected, but passed

through the groove 19. In either case, the fittings jaw teeth 20 then will be inside the working teeth 22 and so disposed as in no way to interfere with the use of the teeth 22 or the passage of the chain. More particularly considering the disposition of the chain 4, it will be evident that when the front bottom teeth 22 on the side jaw plates are in use, the chain will not engage the fittings jaw, but, when the rear bottom teeth 22 are in use, it is possible for the chain 4 to lie in various positions in the chain groove 19 in such manner as to produce an effective action while also preventing the cutting of the chain by the teeth of the fittings jaw which would otherwise soon ruin the chain. In other words, the construction is such that, while having a front fittings jaw thereon, the wrench is still enabled to be used normally and effectively with the side jaw plates thereon, not only in connection with the front teeth on the side jaw plates, but also with the rear teeth 95 on these plates and all without the fittings jaw in any way interfering with normal operation, or abnormally affecting the chain. Attention is further particularly directed to the fact that the front fittings jaw means is herein so disposed to enable the chain to be disposed not only in a proper position to co-operate with either the front and rear side jaws on the side jaw plates, but symmetrically disposed in each of its positions relative to work engaging either of these jaws, the front fittings jaw in my improved construction being so disposed as to permit such a symmetrical disposition of the chain without cutting of the latter when the rear side jaws are in use. It will further be noted that the fittings jaw is enabled 105 to remain permanently connected to the wrench in such manner as to be readily available for use whenever desired upon mere removal of the one bolt 6 holding on the jaw plates 3, or even more quickly, i. e. without this removal, when the size 110 and shape of the fittings permit. In use, it will also be observed that, as compared with previous fittings jaws, less space is required around the pipe and that, accordingly, the improved construction may be used with increased facility 120 when limited space is available.

As a result of my improvement, it will also be noted that the structure has been substantially improved and simplified over those prior constructions of the type wherein the fittings jaw 125 has been permanently connected to the wrench and usable at will with or without the jaw plates. For example, as compared with those constructions wherein the fittings jaw has been located at the rear of the wrench with strap links of the 130 chain on a rivet at opposite sides of and straddling a central fittings jaw, it will be noted that herein it is made possible to utilize a single chain connecting link 29 to connect the chain to the screw 28, to disconnect the link 29 quickly and 135 readily whenever desired, and also to increase substantially the possible width of the fittings jaw. Also, as compared with those constructions wherein the fittings jaw has been held in place by both dowel and bolt connections at opposite 140 ends thereof, it will be noted that only a single centrally located and readily accessible screw 17 is required.

Here attention is also directed to Figure 9 wherein it will be noted that I have shown a 145 modified form of fittings jaw which, if desired, may be used in place of that heretofore described. In this construction, no groove extends throughout the length of the jaw, the teeth instead having a substantially greater effective area and also 150

providing an effective toothed area directly under the chain. It will, however, be noted that in this construction the front tooth is preferably grooved as shown at 36 to provide a short chain passage and thereby avoid cutting of the chain thereby.

While I have in this application specifically described two embodiments which my invention may assume in practice, it will be understood that these embodiments have been shown for illustrative purposes and that the invention may be modified and embodied in various other forms without departing from its spirit or the scope of the appended claims.

What I claim as new and desire to secure by Letters Patent is:—

1. The combination with a chain pipe wrench having on its body a rear chain pivot and a top chain hook, and having a chain pivoted on said pivot and engageable with said hook and also jaw plates provided with front and rear teeth and connected to said body, of front fittings jaw means underlying the front end of the wrench body and provided with means for enabling use of said rear teeth without cutting of said chain by said front fittings jaw means.

2. The combination with a chain pipe wrench having on its body a rear chain pivot and a top chain hook, and having a chain pivoted on said pivot and engageable with said hook and also jaw plates provided with front and rear teeth and connected to said body, of front fittings jaw means underlying the front end of the wrench body and having a longitudinally cut away portion for enabling the chain to be disposed in non-cutting relation to the fittings jaw teeth during use of said rear teeth.

3. A chain pipe wrench having a chain, a chain pivot, a chain hook, jaw plates having front and rear teeth and a connection with the wrench body between said pivot and hook, and a fittings jaw projecting forwardly beneath said hook having a toothed surface and a chain passage in one end thereof for preventing cutting of the chain when the rear teeth on said plates are in use.

4. A chain pipe wrench having a chain, a chain pivot, a chain hook, jaw plates having front and rear teeth and a connection with the wrench body between said pivot and hook, and spaced fittings jaws between said plates presenting a chain passage therebetween for preventing cutting of the chain when the rear teeth on said plates are in use.

5. In a chain pipe wrench, a body having stationary chain carrying lugs, a bolt aperture, and chain hook means, jaw plates on opposite sides of said aperture, a bolt in said aperture connecting said plates to said body, a chain connectible

to said hook means and having a connecting link between said lugs, and a pivot connection for said link remaining connected upon removal of said plates and threaded into one of said lugs.

6. In a chain pipe wrench, a body having chain carrying stationary lugs thereon, a jaw plate connecting aperture disposed out of the path of a chain, and chain hook means, jaw plates having connecting means in said aperture, a chain having a connecting link between said lugs, and a pivot pin for said link remaining connected upon removal of said plates and engaging one of said lugs and threaded in the other.

7. In a chain pipe wrench, a handle having a body provided with a jaw plate aperture, a chain pivoted on said body in rear of said aperture, and a hook on said body in front of said aperture, jaw plates on said body having connecting means in said aperture, fittings jaw means on said body projecting in front of said aperture beneath said hook presenting a longitudinal chain slot between spaced toothed portions thereon, and connecting means for said jaw means between said aperture and hook.

8. In a chain pipe wrench, a handle having a body provided with a jaw plate aperture, a chain pivot aperture on said body in rear of said aperture, a hook on the top of said body, and a rearwardly sloping chain abutment portion on said body below said hook and in front of said plate aperture, jaw plates having front and rear teeth, connecting means for said plates in said plate aperture, a chain having a pivot in said pivot aperture, and front fittings jaw means underlying said abutment portion and presenting a chain passage inside the edge of certain of its teeth in which said chain may be disposed during use of said rear teeth.

9. A fittings jaw for chain pipe wrenches presenting on its working face a set of teeth and having certain of said teeth cut away longitudinally through their working edges to form a chain groove at one end of said jaw for inhibiting cutting of the chain thereby.

10. A fittings jaw for chain pipe wrenches presenting on its working face a plurality of spaced sets of teeth and a longitudinally extending chain groove therebetween extending longitudinally of said jaw through the working edges of certain of said teeth.

11. A fittings jaw for chain pipe wrenches presenting on its working face a set of teeth and having a plurality of said teeth cut through transversely of the same and longitudinally of said jaw to provide a non-cutting chain passage extending around one end of said jaw.
